(57) **CLAIM**

The ornamental design for a headlight for four-wheeled vehicle, as shown and described.

DESCRIPTION

FIG. 1 is a perspective view from the front right side of a first embodiment of a headlight for four-wheeled vehicle.

FIG. 2 is a perspective view from the front left side thereof.

FIG. 3 is a perspective view from the rear right side thereof.

FIG. 4 is a perspective view from the rear left side thereof.

FIG. 5 is a front elevation view thereof.

FIG. 6 is a rear elevation view thereof.

FIG. 7 is a right side elevation view thereof.

FIG. 8 is a left side elevation view thereof.

FIG. 9 is a top plan view thereof; and,

FIG. 10 is a bottom plan view thereof.

The broken lines shown in the drawings illustrate portions of the headlight that form no part of the claimed design.
